UNITED STATES PATENT OFFICE.

JEROME R. GEORGE, OF WORCESTER, MASSACHUSETTS, ASSIGNOR TO
MORGAN CONSTRUCTION COMPANY, OF WORCESTER, MASSACHU-
SETTS, A CORPORATION OF MASSACHUSETTS.

GAS-PRODUCER.

SPECIFICATION forming part of Letters Patent No. 745,176, dated November 24, 1903.

Application filed April 3, 1902. Serial No. 101,142. (No model.)

To all whom it may concern:

Be it known that I, JEROME R. GEORGE, a citizen of the United States, residing at Worcester, in the county of Worcester and 5 Commonwealth of Massachusetts, have invented a new and useful Improvement in Feeding Devices for Gas-Producers, of which the following is a specification, accompanied by drawings forming a part of the same, in 10 which—

Figure 1 represents a top view of a gas-producer provided with my improved feeding device, but having a coal-reservoir removed therefrom in order to disclose the rotating coal-distributer; and Fig. 2 is a vertical sectional view of my improved feeding device and of the upper portion of the gas-producer on line 2 2, Fig. 1.

Similar reference-figures refer to similar 20 parts in the different views.

My present invention relates to a device for accomplishing the uniform and even distribution of coal to the combustion-chamber of a gas-producer; and it has for its object 25 to simplify the construction of the coal-distributing mechanism, to protect it from the injurious effects of overheating, and to secure a uniform feeding and even distribution of coal within the combustion-chamber of the 30 producer, and I accomplish these results by means of the construction and arrangement of parts as hereinafter described, and shown in the accompanying drawings, the novel features being pointed out in the annexed 35 claims.

Referring to the accompanying drawings, 1 denotes the upper portion of a gas-producer having a combustion-chamber 2 of the usual and well-known form of construction. Mount- 40 ed upon the upper end of the producer is a metal top plate 3, having an opening 4 concentric with the combustion-chamber 2, through which coal is fed to the combustion-chamber. The opening 4 is surrounded by an 45

annular flange 5, projecting upwardly from the plate 3. Concentric with the flange 5 and extending upwardly from the plate 3 is a flange 6, which, together with the flange 5, forms an annular trough or water-space 7.

Mounted upon the plate 3, concentrically with the opening 4 and at equal distances apart, are three brackets 8, each supporting a vertical and a horizontal stud, upon which turn the friction-rolls 9 and 10. The friction-rolls 9 support upon their upper surfaces a rotating 55 coal-distributing pan 11, provided with a horizontal bottom plate 12, which extends across the opening 4 a short distance above the annular flange 5. The outer edge of the bottom plate 12 is provided with a depending flange 60 13, which extends downward into the water-space 7, and an upwardly-extending side, forming a rim 14, which incloses a water-space 15. The upper edge of the rim 14 is provided with an outward flange 16, which rests upon 65 the periphery of the friction-rolls 9 and to which is attached an annular rack 17. The edge of the flange 16 bears against the rolls 10, thereby holding the bottom plate 12 from lateral movement, and the rack 17 is engaged 70 by a pinion 18 upon a vertical shaft 19, to which an intermittent motion is given by means of a ratchet-wheel 20, which is actuated by a vibrating pawl 21, driven by an eccentric 22, whereby an intermittent rotary 75 motion is imparted to the bottom plate 12 and coal-distributing pan 11.

The coal-distributing pan 11 is provided with a bottom 23, which is preferably slightly inclined from a horizontal plane and is sup- 80 ported upon a rib 11^a. The bottom plate 12 is provided near one edge with an opening 25, which communicates by a passage 24 with the coal-distributing pan 11, forming a spout-like passage from the coal-distributing pan 11 85 through the opening 25 into the combustion-chamber of the furnace. The opening 25 is located outside and at some distance beyond the vertical plane of the circular side wall 26 of the coal-distributing pan, and the lower 90 edge of the inclined bottom 23 is extended laterally into the coal-passage 24 and is joined to the horizontal bottom plate 12.

The coal-distributing pan 11, with its side wall 26, inclined bottom 23, horizontal bot- 95 tom plate 12, and with its flanges for forming the water seals, as herein described, is cast in a single piece, with an open space between

the horizontal bottom plate 12 and the inclined bottom 23 to allow the water inclosed within the rim 14 to flow from the coal-distributing space 15 into the space between the 5 horizontal bottom plate 12 and the inclined bottom 23, thereby covering the upper surface of the bottom plate 12.

The water-pan 11 is provided with a flange 27, concentric with and outside the side 26, 10 inclosing an annular water-space 28 between the flanges 27 and the side 26 in order to form a water seal between the upper edge of the revolving coal-distributing pan and the lower edge of the stationary coal-reservoir. The 15 coal-reservoir 29, preferably cylindrical in its upper section and having a hopper-shaped lower section 30, is attached to and supported upon three equidistant braces 31, mounted upon the top plate 3 of the producer. The 20 lower end of the hopper-shaped section 30 is provided with a cylindrical flange 32, which extends within the side 26 of the coal-distributing pan, and also with an annular concentric flange 33, which extends into the water-space 28.

Mounted upon the top of the coal-reservoir 29 is a hopper 34 to receive the coal and deliver it to the reservoir 29 through an opening 35 in the top of the hopper 34, said opening 30 being opened and closed at will by a rotating damper 36 of the usual and well-known construction and operated by a lever-handle 37.

Projecting upwardly from the inclined bottom 23 of the coal-distributing pan 11 and integral therewith are the blades 38, which extend into the coal-reservoir 29 and are preferably located slightly eccentric to the axis of rotation of the coal-distributing pan. As the coal-distributing pan is rotated the blades 40 28 serve to agitate the coal within the contracted mouth of the coal-reservoir and prevent it from clogging as it passes downward into the coal-distributing pan 11 and is supported upon its inclined bottom 23. The opening 45 25 through the horizontal bottom plate 12 of the coal-distributing pan is placed far enough outside the vertical plane of the side wall 26 of the pan so that the accumulated coal resting upon the inclined bottom 23 and 50 opposite the opening 25 will lie within the angle of repose and when the coal-distributing pan is at rest will be prevented from flowing by gravity through the opening 25 into the combustion-chamber; but when the 55 coal-distributing pan and mass of coal supported thereon is rotated against the pressure of the superincumbent stationary mass of coal contained in the reservoir 29 the coal upon the inclined bottom 23 will be pushed 60 through the passage 24 and off the lower edge of the bottom 23 through the opening 25 into the combustion-chamber and permitted to fall in an annular path upon the charge of coal 39 contained in the combustion-chamber. As 65 the pieces of coal diverge but little in their descent they form an annular ridge, from which they roll toward the outside and the

center, thereby effecting an even distribution of coal between the center and outside of the combustion-chamber and within the area 70 most favorable for the uniform decomposition of the coal.

Water is conducted by a pipe 40 to the upper water-space 28 of the revolving coal-distributing pan, from which space it overflows 75 at 41, flowing over the arched wall 42, which incloses the coal-passage 24, into the water-space 15, which communicates with the space between the inclined bottom and the horizontal bottom plate 12 and covering the entire upper surface of the bottom plate 12 and flowing around the opening 25. From the water-space 15 it flows through an opening 43 into the lower water-space 7, from which it is conducted by an overflow-pipe 45. The single stream of water through the pipe 40 therefore not only provides the water seal between the upper edge of the coal-distributing pan and the lower edge of the coal-reservoir and also between the coal-distributing pan and 90 the top plate 3, but it also serves to protect the bottom plate 12 from the injurious effect of heat and at the same time to cool the space within the coal-delivery opening 25 and preventing the coking of the coal therein. Should 95 this occur, the coal-passage is accessible by means of an opening in the wall 42, said opening being closed by a plug 46. The under side of the horizontal bottom plate 12 is provided with a series of dovetail projections 47 100 to engage and support a line 48 of fire-clay by which the under side of the bottom plate 12 is shielded from the heat of the producer.

I not only accomplish a very even and uniform distribution of coal within the combustion-chamber by means of my improved coal-distributing device, but, what is of great importance, I am enabled to protect the entire mechanism from injury due to the excessive heat of the producer, and I am enabled to accomplish this result by placing the rotating coal-distributing mechanism entirely above the top plate 3 of the producer and extending the same beyond the central opening to the heating-chamber, whereby a current of 115 water can be maintained upon the upper surface of the bottom plate 12 of the coal-distributing pan.

What I claim as my invention, and desire to secure by Letters Patent, is—

1. In a gas-producer, having an opening in its top communicating with the combustion-chamber, a feeding device comprising a rotating coal-distributing pan placed over said opening and a stationary coal-reservoir placed above said pan and communicating therewith, said coal-distributing pan having an unobstructed passage therethrough, and having an opening at its lower end eccentric to its axis of rotation for the delivery of coal to 130 the combustion-chamber, and an opening at its upper end for the reception of coal from said reservoir, a coal-supporting bottom whereon coal is held at an angle of repose

70

while the coal-distributing pan is at rest, and means for rotating said pan.

2. A feeding device for gas-producers comprising a top plate having an opening concentric with the combustion-chamber of the producer, a rotating coal-distributing pan having an unobstructed passage therethrough and provided with an opening at the top concentric with the axis of said pan for the reception of coal, and an opening at the bottom eccentric to the axis of the pan for the delivery of coal, and a coal-supporting surface between said openings whereon coal in a state of rest is supported at an angle of repose, and means for rotating said pan.

3. The combination with the stationary top plate of a gas-producer having a central circular opening communicating with the combustion-chamber, and a vertical flange concentric with said central opening, of a rotating coal-distributing pan having a horizontal bottom-plate extending over said opening and over said flange, with a water-sealed edge and an inclined coal-supporting bottom with an opening at the top to admit coal upon said inclined bottom, and an unobstructed eccentric opening at the bottom of the pan and at one side of said inclined bottom to deliver coal to the combustion-chamber.

30 4. The combination with the top plate of a gas-producer having an opening communicating with the combustion-chamber, of a rotating coal-distributing pan placed over the opening in said top plate and having an unobstructed passage therethrough for coal from said pan to the opening in said top plate, said coal-passage being diverted from a vertical line, whereby the coal is supported in said pan at the angle of repose and held from being moved through said passage by gravity and a stationary coal-reservoir placed above said rotating pan and communicating therewith, substantially as described.

5. The combination with the top of a gas-producer having an opening communicating with the combustion-chamber, of a rotating coal-distributing pan placed over said opening, said pan having an unobstructed passage therethrough eccentric to its axis of rotation through which coal is delivered from said pan to the heating-chamber of the producer, said passage being deflected from a vertical line, whereby the coal supported in said pan is held at an angle of repose, an inclined bottom in said pan and a stationary coal-reservoir placed above said pan and communicating therewith, substantially as described.

6. The combination with the top of a gas-producer, of a coal-distributing pan by which coal is fed to said producer, said pan having an inclined bottom on which the coal is supported and a passage for the delivery of coal therefrom, said passage being deflected from a vertical line, whereby the coal is held at an angle of repose, a stationary coal-reservoir placed above said pan and communicating therewith, means for rotating said pan

and means carried by said pan for agitating the coal in said reservoir, substantially as described.

7. The combination with the combustion-chamber of a gas-producer, of a stationary top plate having a concentric opening leading to said chamber, an annular water-trough surrounding said opening, a plate forming a 75 cover for said opening and having at its edge a depending flange entering said water-trough, and a coal-distributing pan mounted on said plate, said pan having an opening at its top for the admission of coal and an opening at its bottom for the delivery of coal, said openings being connected by an unobstructed passage at an oblique angle to the axis of said pan, whereby the coal is supported in said passage against gravity while the pan is 80 at rest, and means for rotating said pan, substantially as described.

8. The combination with the top plate of a gas-producer having an opening leading to the combustion-chamber, of an annular 90 water-trough surrounding said opening, a rotating plate covering said opening and having an opening communicating with the opening in said top plate and eccentric thereto, means for rotating said plate, an annular 95 flange on said plate entering said water-trough, a coal-distributing pan mounted on said rotating plate, a passage for coal from said pan to said eccentric opening, said passage being deflected from a vertical line, 100 whereby the coal in said pan is held at an angle of repose, and a coal-reservoir placed above said pan and communicating therewith, substantially as described.

9. The combination with the top of a gas-producer having an opening leading to the combustion-chamber of an annular water-trough surrounding said opening, a rotating coal-distributing pan placed above said opening and having a flange entering said water-trough, said pan having an unobstructed passage therethrough placed at an oblique angle whereby the coal is supported therein against gravity during a state of rest, a stationary coal-reservoir placed above said pan and communicating therewith, means for rotating said coal-distributing pan and an overlapping water-sealed joint between said reservoir and said pan, substantially as described.

10. The combination with the combustion-chamber of a gas-producer having an opening in its top, of a rotating coal-distributing member having a water-sealed joint with the top of the gas-producer, means for rotating the same, a stationary coal-reservoir placed 125 above said rotating member and communicating therewith, and a water-sealed joint between said reservoir and said rotating member, said rotating member having an unobstructed passage therethrough placed at an oblique angle to the axis of said rotating member whereby the coal is supported against gravity during a state of rest, substantially as described.

11. The combination with a gas-producer having an opening in its top, of a plate extending over said opening, means for rotating said plate, a coal-distributing pan mounted on said plate and having an inclined bottom, and a coal-delivery passage leading from the side of said pan downward through said rotating plate eccentrically to its axis.
12. The combination with a gas-producer having an opening in its top for the admission of coal, of a rotating plate covering said opening, said plate having an opening eccentric to its axis of rotation, a coal-distributing pan mounted on and carried by said rotating plate, a passage leading from said pan to the opening in said rotating plate, a rim around said rotating plate for the retention of water

and a water-space between said rotating plate and said pan, substantially as described.

13. In a feeding device for a gas-producer, the combination with a combustion-chamber having an opening in its top for the admission of coal, of a rotating coal-distributing member, comprising a rotating plate forming a cover for said opening, a pan mounted on said plate and having an inclined bottom, a water-space between said inclined bottom and said rotating plate, and a coal-passage leading from said pan through said rotating plate, substantially as described.
